DESIGN FOR A TOOTHBRUSH HOLDER

Paul A. Sodini, Sacramento, Calif.

Application January 10, 1948, Serial No. 143,642

Term of patent 3½ years

(Cl. D4—3.2)

To all whom it may concern:

Be it known that I, Paul A. Sodini, a citizen of the United States, residing at Sacramento, in the county of Sacramento and State of California, have invented a new, original, and ornamental Design for Toothbrush Holder, of which the following is a specification, reference being had to the accompanying drawing, forming a part thereof.

Fig. 1 is a front elevational view of a toothbrush holder showing my new design.

Fig. 2 is a top plan view of the same.

Fig. 3 is an elevational view of the toothbrush holder looking at one side thereof.

I claim:

The ornamental design for a toothbrush holder, as shown.

PAUL A. SODINI.
